UNITED STATES PATENT OFFICE.

LINDSAY S. PERKINS, OF WASHINGTON, DISTRICT OF COLUMBIA, ASSIGNOR
OF TWO-THIRDS TO RALPH DE WITT KELLER, OF NEW YORK, N. Y., AND
WILLIAM D. CAMPBELL, OF WASHINGTON, DISTRICT OF COLUMBIA.

ROTARY FILE-CABINET.

SPECIFICATION forming part of Letters Patent No. 717,713, dated January 6, 1903.

Application filed February 17, 1902. Serial No. 94,459. (No model.)

To all whom it may concern:

Be it known that I, LINDSAY S. PERKINS, a citizen of the United States, residing at Washington, District of Columbia, have invented 5 certain new and useful Improvements in Rotary File-Cabinets; and I do declare the following to be a full, clear, and exact description of the invention, such as will enable others skilled in the art to which it appertains to 10 make and use the same, reference being had to the accompanying drawings, and to the letters of reference marked thereon, which form a part of this specification.

This invention relates to certain new and 15 useful improvements in file-cabinets; and it has for its object, among others, the provision of a rotary file-cabinet adapted specially for containing index-cards, the essential object consisting in the provision of a compact rotary file-cabinet adapted to contain within 20 the most convenient access the greatest possible number of index-cards within a given space.

A further object of the invention consists 25 in the provision of a series of tilting cabinets, in connection with a horizontal rotatable cabinet-case, each of the tilting panels being provided with one or more card-holding drawers, the cabinet being designed to be located in 30 close proximity to the desk of the operator and the panels of the cabinet so arranged as to permit any one of the series of panels to be brought, by the rotation of the case, adjacent to the desk or table where, by tilting the 35 panel containing the drawer or drawers, access to which is desired, to be tilted into a horizontal position above the face of the table, and the drawer or drawers containing the cards to be readily moved out upon the table.

To these ends and to such others as the invention may contain the same consists in the peculiar construction and in the novel combination, arrangement, and adaptation of parts, all as more fully hereinafter described, 40 shown in the accompanying drawings, and then specifically defined in the appended claims.

The invention is clearly illustrated in the accompanying drawings, which, with the let-

ters of reference marked thereon, form a part 50 of this specification, like letters referring to like parts throughout the several views, and in which drawings—

Figure 1 is a side elevation of a card-index file-cabinet constructed in accordance with 55 my invention. Fig. 2 is a horizontal section through the same. Fig. 3 is a central vertical section through the cabinet, showing one of the panels tilted and the slide containing the card-drawers being shown as drawn out 60 upon the top of the table or desk. Fig. 4 is an enlarged detail, in horizontal section, of the locking mechanism, taken on line 4-4 of Fig. 3. Fig. 5 is a horizontal section through a 65 slightly-modified form of the cabinet, and Fig. 6 is a horizontal section through another modified form of device with one of the drawers partially withdrawn from the cabinet.

Reference now being had to the details of 70 the drawings by letter, A designates the cabinet, which in Figs. 1 to 3 of the drawings I have shown as twelve-sided, although it will be at once evident that the number of sides may be varied without departing from the 75 spirit of the invention. The cabinet is to rotate around a central post or standard B, and to insure its being held steady in its rotary movements the weight of the cabinet is supported upon a series of caster-wheels C, which 80 travel within an annular groove or track C', extending around the periphery of the base C². In the drawings I have shown the base portion of the cabinet as mounted upon suitable legs or supports C³. 85

Each of the vertical panels or sides D is at 90 a point intermediate its ends and preferably at its vertical center pivoted to the frame of the casing so as to permit the panel to be tilted into a horizontal position by means of suitable handles d at the upper ends of the panels. Each of the panels so pivoted is provided upon its inner side with a sliding frame E, which is adapted to slide within suitable guides e, extending in the direction of the 95 length of the panel. This slide E is provided with one or more card-holding boxes or drawers E². In the drawings I have shown each

of the slides as provided with a series of these drawers E², the drawers being adapted to be moved transversely of the slide upon which they are carried; but it is at once evident that 5 the number of drawers may be varied and is also evident that instead of having the drawers move at right angles to the direction of the slide, as shown in the drawings, they may be moved longitudinally thereof.

10 The details of construction of the framework of the cabinet are immaterial, though in the present instance I have shown the framework of the cabinet as connected to the central post by suitable braces F.

15 Any form of mechanism adapted to serve as means for simultaneously locking the several tilting panels of the cabinet, against tilting movement, may be employed for the purpose. In the accompanying drawings I have 20 shown a simple and effective means for accomplishing this, the same consisting of a movable annular strip G, extending around the periphery of the base of the cabinet, and adapted to be moved by means of suitable 25 handle g', the shank of which handle extends through a slot g in the casing of the cabinet. This annular strip G is provided with a series of lugs or stops h', the number and relative arrangement of which stops correspond 30 with the number and arrangement of the panels, and the said strip G is connected with a collar K', sleeved upon the central post, by means of radiating arms or cross-brace K. The operation of the locking mechanism is 35 simple and will be readily understood. It will be seen that when the strip G is moved, by means of its operating - handle g', the lugs or pins h', carried by the strip, will be thrown into such positions as to engage the 40 rear edges of the panels and hold the same against tilting movement, and that when the strip G is moved in the opposite direction the required distance, the lugs or pins h' will enter the recesses h in the vertical strips h³, 45 which form the angles of the cabinet, where they will be out of engagement with the panels and will thus admit of the same being tilted. Any suitable key-lock may be employed for locking the strip G against movement.

Upon reference to Fig. 3 of the drawings it will be seen that when one of the vertical panels of the cabinet is pulled down or tilted into a horizontal position the panel will rest 55 upon the top of the desk or table I, when by pulling out the slide E, by means of the knob or handle g³, the drawers g², containing the cards, will be brought into convenient access to the operator or other person having occasion to consult the same.

In Figs. 5 and 6 of the drawings I have shown slight modifications in construction. In Fig. 5 the cabinet is shown as having six vertically-disposed panels or sides, each carrying transversely-arranged card-holding drawers, while in Fig. 6 I have illustrated a construction in which the four sections of the cabinet in rec-

tangular form is shown, each of the sections being vertically pivoted at one of its corners and adapted to be turned by suitable handles 70 k, the tilting panel of each of these pivoted sections being provided with a sliding drawer or frame containing card-drawers, such as I have illustrated in Figs. 1, 2, and 3 of the drawings.

75 The invention is subject to many modifications in detail without departing from the spirit of the invention. I have described and shown a cabinet having a central post around which it rotates; but it is at once evident that 80 this post or standard may be dispensed with, and the cabinet may be so constructed as to adapt it to rotate upon wheels placed beneath it, said wheels being adapted to travel upon a circular track or guideway, as is common 85 in the construction of rotary cabinets, revolving chairs, &c.

I have described and shown the cabinet as adapted for use in connection with a table or desk, the said table or desk forming a support for the tilting panel when the same is turned down into a horizontal position; but the table is merely shown for the purpose of illustrating one of the many ways in which the cabinet may be used, and I do not in this 90 application propose limiting myself to the use of a desk or table or any other specific form of support for the panel when turned down into a horizontal position, as the cabinet is designed for use independent of tables or 95 desks. I have also described a cabinet designed especially for use in connection with drawers such as are designed to retain index-cards; but it is not my purpose to limit myself to a file-case of this description, as the 100 drawers may, if preferred, be used for other purposes, as, for instance, tool-drawers, letter-file drawers, &c.

105 Any form of drawers adapted to the purpose may be used in connection with the cabinet and the drawers may be so adjusted as to permit their removal from the sliding base, should it at any time be desired to remove them.

110 What I claim to be new, and desire to secure by Letters Patent, is—

1. A file-cabinet comprising a rotary frame, pivoted panels mounted on horizontal axes therein, and sliding drawers held to and tilting with said panels, as set forth.

115 2. A file-cabinet comprising a rotary frame, horizontally - disposed pivotal pins carried thereby, panels mounted on said pins, a longitudinally-sliding index-drawer held to each panel and tilting therewith, as set forth.

120 3. A file-cabinet comprising a rotary frame, horizontally - disposed pivotal pins carried thereby, panels mounted on said pins, a longitudinally-sliding index-drawer held to each panel and tilting therewith, and a stop to 125 limit the inner throw of the drawer, as set forth.

130 4. A rotary file-cabinet having a series of horizontally-pivoted panels about its circum-

ference, a slide mounted upon each panel, and means for locking the panels in vertical positions, as set forth.

5. A file-cabinet comprising a plurality of rotatable frames, each pivotally mounted at one of its corners, a tilting panel with horizontal axes carried by each frame, and a sliding drawer held to and tilting with each panel, as set forth.

10. 6. An upright revolving cabinet having a series of faces, each face forming a base or support for a sliding drawer and each support being pivoted at points intermediate of its ends and adapted to be tilted outward and downward upon a desk or other supporting-surface to permit the contents of the drawer or cabinet being inspected, substantially as described.

20. 7. A revolving cabinet of drawers, the drawers being suspended perpendicularly upon tilting bases, said bases being pivotally connected with the frame of the cabinet and adapted to be tilted upon a desk or other support and said drawers adapted to be 25 moved in or out upon the tilting bases, substantially as described.

25. 8. In a file-cabinet, a revolving framework comprising an upright supporting pivot or standard provided with a series of radiating-arms supporting upright standards intermediate of which standards are provided boxes or drawers pivoted between the standards, said boxes being adapted to be tilted forward

and downward upon a supporting-surface, and holding drawers or cabinets of drawers 35 adapted to be drawn out of said boxes upon a supporting-surface, substantially as and for the purpose described.

9. In a file-cabinet, a tilting-drawer support pivoted in such a manner as to allow the 40 drawer to be tilted forward upon a desk or other support, in combination with grooves or guides so arranged as to retain the drawer in place upon the support when the same is tilted, substantially as described. 45

10. In combination with a rotary file-cabinet having a series of tilting sections as described, of locking mechanism consisting of a ring, of somewhat smaller diameter than the cabinet and connected by two opposite spokes 50 to a bearing pivoted loosely around the center post or pivot of the cabinet, a suitable handle attached to the ring and extending through a slot in the cabinet, said handle being adapted to move the ring laterally to 55 cause the lugs or pins upon the ring to engage slots in vertically-disposed posts between the tilting sections, to lock the same against tilting movement, substantially as described and for the purpose specified. 60

In testimony whereof I hereunto affix my signature in presence of two witnesses.
